UNITED STATES PATENT OFFICE

2,198,191

BOOK-MARKING DEVICE

William R. Wheeler, Amherst, Mass.

Application September 29, 1939, Serial No. 297,131

3 Claims. (Cl. 281—42)

My invention relates to marking or indexing means for books and the like and is directed more particularly to the provision of a novel device, adapted to be inserted in a book or the like after the same is bound and fastened therein so as to facilitate the locating of a page or pages or a section or sections therein.

It is a principal object of my invention to provide a novel and improved book marker which can be easily and quickly inserted into a bound book or the like and fastened therein with a portion thereof projecting outwardly beyond a marginal edge of the book in such a way that the user may merely grasp the projecting part and by manipulating the device, readily turn the pages of the book, all to the end that the various pages and the binding of the book are saved from unnecessary damage and mutilation.

As special features, the device of my invention has novel means for facilitating the tight securing thereof in its place in a book or the like. As will appear, the device is unitary and compact in character and is simple yet durable in its construction. By reason of its construction, my improved device may be made economically and with few operations in the manufacture of its parts as well as in assembling thereof.

Various other objects and advantages will hereinafter more fully appear from the following description, in which reference will be had to the accompanying drawing, wherein:

Fig. 1 is a perspective view showing the device of the invention associated with a book;

Fig. 2 is a plan view of one form of the device of the invention;

Fig. 3 is a broken plan view of a modified form of the device of the invention; and

Figs. 4 to 7 are plan views of still other modified forms of the invention.

Referring now to the drawing more in detail, the invention will be more fully described. Like numerals in different figures refer to like parts.

In Fig. 1, a bound book is generally designated by 10 and it may include a pair of cover members 11 and a plurality of leaf members 12 therebetween, the whole being hinged together at adjacent marginal edges in some suitable manner, as to a back-bone member 14. According to the form shown in Figs. 1 and 2, an insert member 16 is disposed between two of the leaves transversely thereof.

The member 16 is in the form of an elongated strip and it may be formed of any suitable stiffish, yet thin material such as cardboard. One end portion of the strip projects beyond the side

marginal edge of the leaves of the book substantially as shown while its opposite end portion is fastened to the binding in one of several ways which will later be more fully explained.

It should be here stated that any desired indications or representations may be printed or otherwise provided on the inserts; that is to say, appropriate letters or figures or other characters may be printed on the body of the strip and/or on its free end portion to indicate anything desired such as the page or section of the book which it marks and to assist the user in the handling thereof. Both the strip shown in Figs. 1 and 2 and the modified forms of inserts which will later be described may consist of strong paper, parchment, cloth, or other suitable material. It will be understood that the inserts may vary in width and length according to the need in the particular case.

In Fig. 2, one end of the strip 16 is provided with a pair of spaced holes through which arms 18 of a bendable prong member extend. The arms may be connected by a transverse part 20 and the arms and part 20 may be formed of a unitary piece of wire or the like.

The bendable arms 18 are forced through the hinge 14 of the book and then bent over to be adjacent to the outer surface of the backbone of the book, as shown in Fig. 1. In this way the insert is securely fastened in place with the projecting end portion free to be manually engaged.

While the entire device shown in Fig. 2 may be made from readily bendable material such as wire, it falls within the invention to provide a device wherein the arms beyond the insert are relatively more bendable than the part or parts thereof which are associated with the insert. This feature applies to the form of the invention shown in Fig. 2 as well as to the forms thereof to be described.

According to the modification in Fig. 3 there are a pair of similarly shaped secured together insert strips 22 with a U-shaped clip held therebetween. The strips 22 in this case are preferably secured together as by adhesive which serves to hold the clip in place.

Said clip has the free end portions of spaced arms 24 projecting beyond the inner end of the secured together strips while a connecting part 26 is disposed between the strips. The free ends of arms 24 are preferably pointed and bendable similarly to the arms 18 so that they may be inserted in or pushed through the backbone of the book in the manner described with reference to Fig. 1.

In Fig. 4, another modified form of the device of the invention is shown. Here an insert strip 28 has arms 30 of a clip extending through suitable holes in it with the arms extending throughout almost the entire length of the insert. The clip thus serves to act as a re-enforcement for the insert member to stiffen the same for obvious purposes. The transverse part of the clip is shown at 32. In this case, if desired, these may be superposed and secured together insert members, as in Fig. 3, with the clip between said members so that the insert is reinforced substantially throughout its length.

In Fig. 5, there are a pair of rods 34, spaced apart and preferably in parallelism which may extend through slots provided in an insert 36. These rods have pointed end portions projecting beyond one end of the insert 36 and these are for functioning in the same manner as are the members 18, 24, and 30 previously described.

The opposite ends of the rods 34 are bent upon themselves at 38 so as to prevent their detachment from strip 36. The rods are preferably formed of some suitable wire or the like, while in the form shown in Fig. 5, two rods 34 are shown, it will be understood that one or more may be employed.

In another way these may be superposed and secured together insert members with the members 34 therebetween to provide a unitary structure similar to the form of the invention shown in Fig. 3.

Another modification is shown in Fig. 6. In this form of the invention an insert is indicated by 40 and one or more clips or staples have arms 42 extending through the insert and an offset connecting part 44 disposed adjacent the insert.

In Fig. 7 the insert 46 is larger and may more or less correspond to the size of the book's leaves 40 with a projecting tab part 48. There may be one or more staples or clips, such as shown, with arms 50 and connecting parts 52. This insert may consist of secured together superposed members with the clip or clips taking the form of the various clips heretofore described.

From the foregoing it will be observed that the insert may include a single member of various materials a multiple plus of material secured together in superposed relation. The various forms of inserts may be provided with clips having a pair of prongs, or there may be one or more members to provide the prongs. The clips may include arms connected by transverse members such as in Fig. 2, and the clips may have any desired number of arms or prongs or there may be separate members as in Fig. 5 which are not connected at their ends by a transverse member. There may be any number of clips associated with an insert, or any number of separate members and the clips or members may be associated with the end portion of an insert adjacent either at one side thereof or extend between the members forming the insert. As explained a clip or separate members may extend along an insert or be disposed between superposed members forming the insert for reinforcing purposes.

While I have described the invention in great detail and with respect to the present preferred

form thereof, it is not desired to be limited thereto since changes and modifications may be made therein without departing from the spirit and scope of the invention. The invention may be embodied in other specific forms without departing from the essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What it is desired to claim and secure by Letter Patent of the United States is:

1. As a new article of manufacture, a device for marking a bound book comprising in combination, an insert member consisting of an elongated, relatively thin, and flat strip adapted to have its main body portion lie flat and horizontally between adjacent leaves of a book and an outer end portion project outwardly beyond side edges thereof, and a separate securing member having an inner end part attached to said insert member and horizontal intermediate parts extending beyond the inner edge of the insert member and adapted to extend through the binding of the book and outer end parts adapted to be bent on angles to said intermediate parts and to lie adjacent the outside of the binding so as to prevent withdrawal of the insert member from between the leaves.

2. As a new article of manufacture, a device for marking a bound book comprising in combination, an insert member consisting of an elongated, relatively thin, and flat strip adapted to lie horizontally and flat between adjacent leaves of the book and project outwardly beyond side edges thereof, a separate securing member consisting of a U-shaped clip having horizontal arm portions connected by a vertical transverse portion, said arm portions extending through openings in said insert member so that they are disposed adjacent one face of the insert member and the transverse portion is disposed adjacent the opposite face of the insert member, said arm portions extending beyond the inner end of the insert member and adapted to extend through the binding of the book and to be bent over to lie adjacent the outside of the binding so as to prevent withdrawal of the insert member from between the leaves.

3. As a new article of manufacture, a device for marking a bound book comprising in combination, a relatively thin and flat insert member adapted to have its main body portion lie flat between adjacent leaves of the book and an outer edge portion project outwardly beyond side edges thereof, and securing members extending beyond the inner edge of said insert member and adapted to extend through the binding of the book, the outer end parts of said securing members being adapted to be bent over to lie adjacent the outside of the binding so as to prevent withdrawal of said insert member from between the leaves.

WILLIAM R. WHEELER.
